UNITED STATES PATENT OFFICE.

FRANCIS W. TULLY, OF BROOKLINE, MASSACHUSETTS.

GAME APPARATUS.

1,245,640.

Specification of Letters Patent.

Patented Nov. 6, 1917.

Application filed November 17, 1916. Serial No. 131,897.

To all whom it may concern:

Be it known that I, FRANCIS W. TULLY, a citizen of the United States, and resident of Brookline, in the county of Norfolk and 5 State of Massachusetts, have invented new and useful Improvements in Game Apparatus, of which the following is a specification.

This invention relates to game apparatus. 10 One object of the invention is to provide a device adapted for the consecutive selection and disclosure of an arbitrary series of numbers, names, words or symbols. Another object is to provide apparatus 15 forming such a consecutive selection and disclosure by means designed to attract the interest and attention of observers. A further object is to provide apparatus of the nature mentioned associated with a source 20 of light, for the further enhancement of the attraction worked upon the mind of the observer.

So far as I am aware, apparatus for the selection of a sequence of numbers, symbols, 25 or objects adapted to introduce the element of chance, has heretofore comprised broadly spinning devices such as whirling pointers, roulette wheels, etc.; varieties of dice, depending in principle on the random position- 30 ing of a geometrical solid bearing different symbols on its faces; and the random arrangement of cards or other objects adapted to be selected and disclosed one at a time from a pack or a receptacle.

35 My present device belongs broadly to the last mentioned group, but differs from it radically in employing a previously fixed but effectively concealed series of numbers or symbols, etc., and in providing means for 40 the consecutive disclosure and subsequent destruction of each element of the device bearing a number or symbol.

I shall describe my invention in connection with a preferred species comprising a 45 container of a fusible nature for a concealed series of objects, numbers or symbols, the container being adapted to be removed from the objects contained by the application of heat, and preferably consisting of 50 a wax, tallow, stearin or paraffin candle having a series of numbers, symbols, etc., concealed in its substance and adapted to be

exposed as the candle is melted and burned away by the operation of a wick in the usual manner.

In the accompanying drawings,

Figure 1 is an elevation illustrating one form of my device in use;

Fig. 2 is a perspective;

Fig. 3 is a section on line 3—3 of Fig. 1, 60 showing the relation of a wick, a symbol carrier and the container;

Fig. 4 illustrates a different form of wick and symbol carrier;

Fig. 5 is a section on line 5—5 of Fig. 4; 65

Fig. 6 illustrates another form of symbol carrier, and modified means for destroying the previously selected symbol;

Fig. 7 illustrates another form of symbol carrier and its relation to a wick; and 70

Fig. 8 illustrates a wick and a series of detached symbols carried thereby.

Referring now to Figs. 1, 2 and 3, 1 is the body of a container made as a candle selected to illustrate the principle of the 75 invention. Said candle may be cast or molded in any usual manner from any usual substance, typically consisting of paraffin, stearin, or other waxy substance. The usual wick 2 is centrally disposed in the body 1. 80 Adjacent to the wick and if desired attached thereto in any convenient manner, I provide a symbol carrier 5 which may consist as shown of a strip of paper having an arbitrary series of numbers (or other symbols) 85 printed on one face.

Upon lighting the candle comprised of the body 1 and wick 2, the symbols on the symbol carrier 5 are successively exposed, as 90 illustrated in Fig. 1, by the approaching flame as the candle burns down, and the carrier 5 is thereafter consumed with the wick from above a point relatively close to the flame. The substance of the candle conceals the symbol carrier except at the end 95 bearing the exposed symbol.

As illustrated in Fig. 2, means may be provided for preventing the partial consumption of a symbol space 6 of the symbol carrier 5 before the complete disclosure of 100 this symbol space. Preferred means for this purpose consists of an applied line or spot 7 of fireproofing composition applied to the symbol carrier 5. I prefer to saturate a

transverse portion 7 with a solution of sodium silicate, for instance one part of sodium silicate in two parts of water. This fireproofing solution may be applied to the 5 whole strip or carrier 5, and in that case only the relatively high heat from the direct flame of the candle will result in combustion.

Preferably when the strip 5 is either 10 homogeneously coated or contains the bars or spots 7 only of fireproofing, I prefer to attract attention to the complete appearance of a new symbol space by some change in the candle flame. One way of doing this is 15 illustrated in Fig. 2, comprising spots or zones 8 on the wick 2, impregnated with a substance to induce a more lively combustion, such as will follow from applying to the wick at the portions 8 a solution of one 20 part of chlorate of soda in two parts of water, or by applying thereto a solution of potassium nitrate, or by applying to the wick at these places a pyrotechnic composition of any known or suitable sort to produce a change in the flame of the candle 25 when the flame reaches the places 8.

Instead of employing a round wick 2 with the symbol carrier 5, I may employ a flat wick 10 of a woven, knit or braided textile fabric, suitably attached to the symbol carrier 5, for instance, by a melted waxy substance similar to that of the body 1. But 30 in some cases symbols may be printed or formed directly on such a flat wick, and a separate carrier 5 is then dispensed with, 35 the wick itself being the carrier.

As shown in Fig. 4 the wick 10 may have 40 transverse elements 11 which have been previously impregnated in the same manner or with the same substances as explained above in connection with the parts 8 of the wick 2. For making, the wicks 10 and the strips 5 may be formed in sheets attached 45 together, and then cut to the width desired.

Preferably the flat wick in use is centrally 50 positioned in the body 1, as shown in Fig. 5.

As illustrated in Fig. 6, instead of inducing 55 a change in the flame of the candle at intervals, I may provide for the destruction of a portion of the symbol carrier already exposed in a way to attract attention. As there shown, in association with a wick 2 of any of the kinds described above, the symbol carrier may consist of two layers 12 of paper, preferably provided with the fireproofing 7 as described above, and with perforations 13 separating the strip 12 into the symbol spaces as shown. In each symbol space and between the layers 12, I now provide a pyrotechnic pellet 14, which may be 60 a chlorate mixture containing a coloring ingredient, such as strontium nitrate, or may be a mild explosive of any usual kind to produce a sound as well as the destruction of the symbol space containing it whenever

the flame heats it beyond the critical temperature at which it is designed to ignite. 65

As shown in Fig. 7, I may provide a symbol carrier in the form of a fusible metallic strip 15, having the symbols stamped in or otherwise formed thereon, and in that case 70 I prefer to wind the wick 2 about reduced portions of the symbol carrier 15 as shown. The symbol spaces 17 may, if desired, be formed by flattening the round wire of which the carrier 15 originally consisted. 75 In use, the symbol spaces 17 are exposed successively by the melting of the body 1 with which the parts shown in Fig. 7 are surrounded, and the symbol spaces are successively destroyed by melting in the heat of 80 the candle flame.

As illustrated in Fig. 8, separate symbol carriers 18 may be attached to the wick 2. With this form of my device the carriers 18 85 preferably are paper tags having arms 19 adapted to surround the wick 2, or to be passed through the substance thereof (not shown).

In any form of my device the symbols carried by the symbol carrier may be arranged at random so that the probability of 90 finding two or more candles having the same symbols in the same order is very remote.

It will be obvious that a number of different games depending on the elements of chance may be played during the consumption of a candle formed as described. Each player may be provided with one candle and win or lose in respect to the other as the 95 numbers exposed by his candle are larger or smaller, or different symbols may be assigned different arbitrary values accruing to one or the other player either as the symbols are exposed on individual candles or as they 100 are taken in alternation by each player to 105 his own credit.

Within the principle of my invention the apparatus obviously may be employed for amusement or instruction in any desired 110 manner, being independent of the particular symbol, letter, word or number disclosed; and the device may be employed to expose in sequence any concealed message, word or sentence, as well as an arbitrary 115 sequence of symbols. While I have illustrated and described in explanation of the genus several species of apparatus, many other varieties unnecessary specifically to show or describe obviously are included 120 among the forms in which the apparatus may be exemplified without departure from my invention.

What I claim is:

1. Game apparatus comprising a container; a symbol carrier adapted to bear a series of symbols, words, numbers or the like concealed in said container, said con-

tainer being adapted to be ignited whereby to consecutively expose and subsequently destroy portions of the symbol carrier.

2. Game apparatus comprising a fusible container, a symbol carrier adapted to bear a series of symbols, words, numbers or the like concealed in said container, said container being adapted to be ignited whereby consecutively to melt away portions of the container whereby to expose the symbols successively.

3. Game apparatus comprising a container adapted to be ignited at one end and thereby consumed, and a symbol carrier normally concealed in the substance of said container whereby to be exposed at the burning end.

4. Game apparatus comprising a candle and a symbol-carrier embedded in said candle.

5. Game apparatus comprising a candle having a wick and a symbol carrier associated with the wick embedded in said candle.

6. Game apparatus comprising a candle and a symbol-carrier adapted to resist con-

sumption by heat to a greater degree than the substance of the candle embedded in said candle.

7. Game apparatus comprising a candle and a symbol-carrier having symbol-spaces whose first exposed edges are adapted to resist consumption by fire, embedded in said candle.

8. Game apparatus comprising a container adapted to be ignited and consumed, and a normally concealed symbol-carrier therein adapted to be exposed at the burning end, said carrier having associated therewith a pyrotechnic or explosive substance.

9. Game apparatus comprising a candle having a textile wick bearing a series of symbols for consecutive exposure at the burning end of the candle.

10. Game apparatus comprising a candle having a flat textile wick and a flat paper symbol-carrier associated therewith.

Signed by me at Boston, Massachusetts this eleventh day of November, 1916.

FRANCIS W. TULLY.
